UNITED STATES PATENT OFFICE.

HENRY KEAN, OF KINNICKINNICK, WISCONSIN.

CHURN.

SPECIFICATION forming part of Letters Patent No. 276,598, dated May 1, 1883.

Application filed June 7, 1882. (No model.)

To all whom it may concern:

Be it known that I, HENRY KEAN, a citizen of the United States, residing at Kinnickinnick, in the county of St. Croix and State of Wisconsin, have invented a new and useful Improvement in Churns, of which the following is a specification, reference being had to the accompanying drawings.

My invention consists in a churn embodying certain details of improved construction, which are hereinafter described, and specifically pointed out in the claims.

In the drawings, Figure 1 is a side view, and Fig. 2 an end view, of a churn embodying my invention. Fig. 3 is a central longitudinal section, and Fig. 4 is a transverse section taken on line 1 1 in Fig. 3.

The churn is preferably nearly or quite cylindrical, being composed mainly of the body A, ends B and C and cover D. The body A is formed of several pieces, a. Each of these pieces is of the curved form, and they are tongued and grooved together, being drawn closely to each other and held firmly in place by means of bolts b. These bolts also pass through the ends B and C and through the legs E, as shown. Thus the parts of the body, ends, and legs are securely held in position and closely joined by the bolts and nuts c. Each of the pieces a is formed of two parts, halved together at or near the bottom of the churn, as shown at d, such construction economizing stock. The cover D is also made of several curved pieces, e, tongued and grooved, and held together by bolts or screws f, passing through the same. There are cross-pieces or ledges g fastened longitudinally along the upper edges of the body A. A portion of one edge face of the cover D is cut away, forming an air-space, h, when the cover is in place. Each arm F of the dasher is V-shaped, having the sharp edge i at the front, as the arm will commonly travel, and a groove, j, at the rear. This shape and the groove tend to cause greater motion of the liquid and to mingle air therewith. The arms F are fastened to or shaped to be driven in the axle or shaft G. This axle is supported at one end on the point of a screw

or pin, k, and at the other end on the squared or angular end of a shaft, H. This shaft passes 50 through the bearing and stuffing-box I, and through a stand or strap, J, fastened on the outside of the churn, so as to leave a space between it and the end of the churn. There is a pinion, K, on the shaft H, between the strap 55 J and box I. This pinion and shaft may have a slight endwise motion when the latch L is raised. This latch is pivoted at l, and when down fills the space between the strap J and pinion K. By raising this latch and pulling 60 the shaft H endwise outward by means of the knob m, the angular end of this shaft is withdrawn from the end formed to receive and conform to the end of shaft H of the axle G, and the dasher may be removed from the churn. The 65 latch L, when down, will keep the angular end of shaft H in end of axle G, and the dasher may be revolved by means of the shaft H. On another shaft, n, is a gear, M, which engages with the pinion K and a crank, N. The stuffing-box consists of the part o, fixed to the churn, and a cap, p, to screw thereon. Hemp or other suitable material, q, wound around the shaft and compressed by means of the cap p, prevents the escape of the liquid at this 75 place. A plug, r, is inserted in one side near the bottom of churn, by withdrawing which the churn may be emptied of liquid. In the upper part of one side is fixed a small glass plate, O.

I claim as my invention—

1. A churn in which both the body and cover are formed of several curved pieces, tongued and grooved together, and having bolts or screws which extend through said curved pieces 85 in a direction longitudinal with the body or case, substantially as shown and described.

2. The combination of body A, of several curved pieces, ends B and C, legs E, and bolts b, extending through said curved pieces, ends, 90 and legs, substantially as set forth.

HENRY KEAN.
